CLAIM

The ornamental design for a apparatus for diluting chemical concentrates, as shown and described.

DESCRIPTION

FIG. 1 is a perspective view of the apparatus for diluting chemical concentrates showing my new design; FIG. 2 is a bottom plan view of the apparatus for diluting chemical concentrates;

FIG. 3 is a right side elevational view of the apparatus for diluting chemical concentrates;

FIG. 4 is a left side elevational view of the apparatus for diluting chemical concentrates;

FIG. 5 is a front elevational view of the apparatus for diluting chemical concentrates;

FIG. 6 is a rear elevational view of the apparatus for diluting chemical concentrates; and,

FIG. 7 is a top plan view of the apparatus for diluting chemical concentrates.

FIG. 1

FIG. 2

FIG. 3

FIG. 4

FIG. 5

FIG. 6
